UNITED STATES PATENT OFFICE.

JOHN B. HADAWAY, OF SWAMPSOFT, MASSACHUSETTS, ASSIGNOR TO UNITED SHOE MACHINERY CORPORATION, OF PATERSON, NEW JERSEY, A CORPORATION OF NEW JERSEY.

SOLE-EDGE-TREATING TOOL.

1,381,917.

Specification of Letters Patent. Patented June 21, 1921.

Application filed September 8, 1919. Serial No. 322,445.

To all whom it may concern:

Be it known that I, JOHN B. HADAWAY, a citizen of the United States, residing at Swampscott, in the county of Essex and State of Massachusetts, have invented certain Improvements in Sole-Edge-Treating Tools, of which the following description, in connection with the accompanying drawings, is a specification, like reference characters on the drawings indicating like parts in the several figures.

This invention relates to machines having vibrating tools or irons employed in the manufacture of boots and shoes, as tools for burnishing, polishing, rubbing, shaping, pounding, or otherwise treating the sole edges.

In machines of this character heretofore proposed it has been customary to employ a tool having a single bed surface for operating on the sole edge and such machines are entirely satisfactory when the marginal portions of the soles are uniform in thickness.

Most tools of the character referred to consist of single members and when they are constructed with the usual lips they are incapable of operating upon a sole edge which may slightly exceed the width of the face of the tool between such lips.

A particular object of the present invention is to provide an edge setting tool the utility of which is not limited to operation upon material having a limited maximum width, and to this end a special feature of the invention consists in a tool comprising a plurality of members and having guiding lips, said members being relatively movable to vary the width of the tool as a whole.

A further object of my present invention is to provide a sole edge setting tool which will automatically accommodate itself to varying thicknesses of different portions of the sole edge.

An important feature of this invention is a tool comprising a holder and a plurality of edge finishing irons yieldingly carried by the holder and so constructed and arranged that while the tool is adapted to operate properly while in normal condition upon a sole edge of uniform thickness, yet if a sole edge portion which is of different thickness is encountered, the tool as a whole

will automatically adapt itself to such thickness as by spreading or widening.

In the illustrated embodiment of the invention, a holder is provided having a plurality of edge finishing irons mounted side by side and in close relationship, the irons being yieldingly supported by the holder.

While the invention is useful in various relations, as, for example, in connection with edge setting machines of a type which requires the operator to shift the work manually along and in contact with the setting tool, the illustrated embodiment of the invention is designed with particular reference to machines of the automatic type such as illustrated and described in Letters Patent No. 1,048,174, granted Dec. 24, 1912, upon the application of F. B. Keall.

When single tools are used in automatic machines of the type illustrated in said patent, they are pivotally mounted on an axis parallel to the sole edge in order that the working face of the tool may adjust itself to the edge of the sole and operate upon all parts of it. The axis about which the tool swings passes through the middle of the bed of the tool.

Another important feature of the present invention resides in a finishing tool constructed and arranged so as to make it certain that all parts of the edge will be finished regardless of minor variations in the thickness of the sole edge.

Figure 1 of the accompanying drawings is a perspective view illustrating the invention as applied to a machine of the type explained in the patent hereinbefore referred to.

Fig. 2 is a detail side elevation, partly broken out, of the preferred embodiment of my invention.

Fig. 3 is an elevation looking from the left of Fig. 2.

Fig. 4 is a view similar to Fig. 2 but illustrating a modification; and

Fig. 5 is a broken out perspective view of the form of holder and its irons shown in Fig. 4.

The tool carrier 12 which, it is to be understood, is to be mounted in the machine to be vibrated in any well-known or preferred manner, is formed with a recess 13 above and below which are stop

shoulders 14. Midway of the stop shoulders and extending transversely of the recess 13 the carrier is formed with a bearing 15 to serve as a pivot for the irons 16 of 5 which three are shown in the drawings. I do not limit myself to this number, however, as two may be employed or more than three.

Each iron 16 has a tapering rear portion 10 17 which is mounted upon the bearing 15. The irons are retained in position side by side by means of washers 18 and screws 19 passed into the ends of the bearing 15.

Each iron has a bed face of any preferred 15 configuration with a lip 20 at each end of said bed face. Sometimes one of the lips is called a guard, and has a different shape from that illustrated in the drawings. For present purposes it is sufficient to illustrate 20 the upper and lower lips 20 as having the same configuration.

Each iron has a leaf spring 21, secured by a screw 22 passed into the carrier 12, bearing upon its upper or its lower edge. 25 As shown by comparing Figs. 2 and 3, the springs act alternately in opposite directions upon the irons so as to hold them normally in position with their lips out of lateral alinement so that the bed of the tool 30 as a whole will automatically accommodate itself, as to width, to the width of the sole edge operated upon.

Assuming that the sole, the edge portion of which is indicated at S in Fig. 2, is of 35 just the relative width indicated in the figure, the irons will retain the relative positions illustrated in Figs. 2 and 3. As work progresses along the sole, however, if a thicker portion of the sole edge is encountered, the 40 irons automatically shift toward a position where their lips will be in lateral alinement, without, however, causing any portion of the acting face of either iron or tool to project beyond the acting face of an adjacent iron or tool. In other words, it may be stated that 45 the tool as a whole has a laterally expandible operating surface all portions of which, between the lips 20, remain in the original operating surface during all movements of 50 the members 16 relatively to each other. As soon as any such thicker portion of the sole edge has been passed, the springs 21 automatically return the irons toward or to 55 their normal positions which are determined by the stop shoulders 14.

I do not limit myself to providing a pivotal connection between the irons and the carrier. For instance, as shown in Figs. 4 and 5, the irons may be mounted to slide. 60 In said figures the tool carrier is indicated at 30, said carrier having a plurality of recesses 31 in which are transversely mounted rolls 32. Vertical guideways 33 in the side walls 65 of the recesses 31 are engaged by rib formations at the rear of the irons 34 hav-

ing lips 35. Springs 36 secured to the carrier by screws 37 bear upon the sliding irons to hold them normally in the relative positions indicated in the drawings. In the operation of a machine having a tool of the 70 character illustrated in Figs. 4 and 5, the automatic shifting of the irons under the control of the sole edge itself is effected in the same manner as hereinbefore described in connection with Figs. 2 and 3. 75

In Fig. 1 I have illustrated certain parts of the machine of the Keall patent hereinbefore referred to, said Fig. 1 illustrating said parts substantially as they are illustrated in Fig. 4 of the said patent. To facilitate an understanding of the particular utility of the present invention in a machine of the Keall type, the parts have the same reference numerals as in that patent. Said parts include two feelers 50, 52, the feeler 50 being actuated by a lever 56 carried by a rockshaft 58. The lever 60 performs an operation unnecessary to describe in the present case. The feeler 130 is carried by a rockshaft 138 and the feeler 142 is carried by 90 the rockshaft 146, another arm 144 of which is connected to the tube 134 through which the rod 136 passes. The feeler 52 is operated by the lever 76 and the latter is connected with the rod 80 extending through the tube 95 62. Since the particular operation of these feelers and how they control the automatic operation of the machine of the Keall patent has no bearing upon the present invention, reference may be had to the said patent for 100 a complete description thereof.

In the form of invention illustrated in Figs. 2 to 5 inclusive, the springs act to normally maintain the irons with their lips out of lateral alinement so that the bed portions of the irons will act properly along the sole edge regardless of such ordinary variations in thickness of the sole edge as is liable to occur. 105

It is to be understood that I do not limit myself to the particular shape of the acting faces of the irons illustrated since the irons may be shaped to best suit the work to be performed. 110

Having now described my invention, I 115 claim:

1. In a sole-edge setting machine, the combination with tool operating mechanism, of a plurality of tools side by side and yieldable independently of each other in parallel planes, in a direction tangential to their operating surface. 120

2. A tool for a sole edge setting machine comprising a plurality of edge finishing members mounted side by side and having guiding lips, said members being relatively movable to vary the operative width of the tool as a whole. 125

3. In a sole-edge setting machine, a holder, and a plurality of edge finishing irons yield- 130

ingly carried thereby side by side, said irons being mounted to present their operative surfaces in substantially the same profile during all movements of the irons relatively to each other.

4. In a sole-edge setting machine, a holder, a plurality of edge finishing irons movably connected with said holder to shift relatively to each other in parallel planes, said irons having guiding lips, and means for yieldingly maintaining the irons with their lips out of lateral alinement.

5. In a sole-edge setting machine, a holder, a plurality of edge finishing irons which are duplicates of each other in shape, movably connected with said holder to shift relatively to each other in parallel planes, said irons having guiding lips and means for yieldingly maintaining the irons with their lips out of lateral alinement.

6. A tool for a sole-edge setting machine comprising a holder having a fulcrum, a

plurality of irons having guiding lips mounted side by side to rock on said fulcrum, and means for yieldingly maintaining the irons with their lips out of lateral alinement.

7. A tool for a sole-edge setting machine comprising a holder, a plurality of irons having guiding lips movably mounted side by side in said holder, and springs bearing on the irons to hold them normally in positions with their lips out of lateral alinement.

8. A tool for a sole-edge setting machine comprising a holder having a fulcrum, a plurality of irons having guiding lip mounted side by side to rock on said fulcrum, and springs bearing on the irons to hold them normally in positions with their lips out of lateral alinement.

In testimony whereof I have signed my name to this specification.

JOHN B. HADAWAY.

It is hereby certified that in Letters Patent No. 1,381,917, granted June 21, 1921, upon the application of John B. Hadaway, of Swampscott, Massachusetts, for an improvement in "Sole-Edge-Treating Tools," an error appears in the printed specification requiring correction as follows: Page 3, line 36, claim 8, for the word "lip" read *lips*; and that the said Letters Patent should be read with this correction therein that the same may conform to the record of the case in the Patent Office.

Signed and sealed this 4th day of October, A. D., 1921.

[SEAL.]

KARL FENNING,

Acting Commissioner of Patents.
